UNITED STATES PATENT OFFICE.

MALCOLM FORBES, OF WARWICK, NEW YORK.

SCARF-HOLDER.

SPECIFICATION forming part of Letters Patent No. 396,994, dated January 29, 1889.

Application filed September 10, 1888. Serial No. 285,057. (No model.)

To all whom it may concern:

Be it known that I, MALCOLM FORBES, a citizen of the United States, residing at Warwick, county of Orange, and State of New York, have invented certain new and useful Improvements in Scarf-Holders, of which the following is a specification.

My invention consists in a modification of a breastpin adapting it to serve as a scarf-holder.

Reference is made to the claims for the novel points, the invention being first fully described with reference to the accompanying drawings, in which—

15 Figure 1 represents my improved scarf-holder in front elevation; Fig. 2, the same in side elevation.

The object of the invention is to provide a scarf-holder which will effectually hold the scarf down to its position on the shirt-front, so as to prevent its discommodeing the wearer, the holder being at the same time out of sight, small, and easily attached.

1 represents the breastpin or brooch proper, 25 of any ordinary or preferred ornamental or plain construction, having the customary spring safety-pin, 2. The front of the breastpin is provided with one or more downwardly-projecting sharpened pins, 3, which may be 30 straight or slightly curved outwardly. By the "front" of the breastpin is meant the whole front elevation of the pin, as shown in Fig. 1.

The construction of the scarf-holder is such 35 that the safety-pin 2 may be passed through the shirt-front, either through a solid portion thereof or through a stud-hole therein, so as to avoid marring the shirt-front by two holes.

When in position, it is held by the customary eyelet, 4. The scarf having been applied, is 40 drawn down, so as to be engaged by the point 3, and is so held from rising to the discomfort of the wearer. The point may be of any suitable shape in cross-section. Preferably it is round. It may be varied in length as desired. 45

It will be seen that a scarf-holder of this form needs no plaits to keep it in place. It is wholly concealed from sight, however narrow the scarf may be. It cannot be dropped off or lost when the scarf is removed for any 50 purpose. It is ornamental and simple in construction and can be cheaply made. It may be attached to any point of the shirt-front, according to the length of the scarf worn.

Although, as stated, the projection 3 may 55 be straight or slightly curved, it is preferably made of the latter form, so as to more readily enter the rear fold of the scarf.

Having thus described my invention, the following is what I claim as new therein and desire to secure by Letters Patent:

1. A breastpin scarf-holder consisting of the breastpin proper, 1, having on its rear the safety-pin 2 and on its face the sharpened downwardly-projecting pin 3, substantially as 65 and for the purposes set forth.

2. A breastpin scarf-holder consisting of the breastpin proper, 1, having on its rear the safety-pin 2 and on its front the sharpened downwardly and outwardly projecting pin 3, substantially as and for the purposes set forth.

MALCOLM FORBES.
